ELECTRIC SWITCH

Robert S. Craig, Robbinsdale, Minn., assignor to
Minneapolis-Honeywell Regulator Company,
Minneapolis, Minn., a corporation of Delaware

Application October 7, 1937, Serial No. 167,765

5 Claims. (Cl. 200—152)

This invention relates to liquid flow switches and more particularly to mercury switches.

The prime object of this invention is to provide a liquid flow switch which in one operative position will complete a first circuit, and when moved toward another operative position will complete a second circuit before breaking the first circuit, but when moved back toward its first position will break the second circuit before re-making the first circuit.

Other objects and advantages will become apparent to those skilled in the art upon reference to the accompanying specification, claims and drawings.

15 In the drawings.

Figure 1 is a sectional view of one embodiment of the invention shown in a position in which one circuit is closed;

20 Figure 2 is a sectional view of the switch of Figure 1 in the position in which both circuits are closed;

Figure 3 is a sectional view of the switch shown in Figure 1 in the position in which the second circuit only is closed;

25 Figure 4 is a sectional view of the switch shown in Figure 1 in open circuit position;

Figure 5 is a sectional view of another embodiment of the invention in which one circuit is closed;

30 Figure 6 is a sectional view of the switch shown in Figure 5 in which both circuits are closed;

Figure 7 is a sectional view of the switch shown in Figure 5 in which a second circuit only is closed, and

35 Figure 8 is a sectional view of the switch shown in Figure 5 in open circuit position.

In the embodiment of the invention shown in Figures 1 through 4, like reference characters refer to the same parts in the several views. The switch envelope 10 is made of glass or other insulating material and is tubular in form. The lower exterior surface or floor 11 of the envelope 10 is substantially straight for the greater part of its length. The usual sealing-off tip 12 in this illustrative embodiment is located at one end of the envelope 10 and on the lower side thereof, thereby forming a depression 13 on the inside of the tube. Electrodes 14, 15 and 16 extend into the tube, their inner ends being positioned close to the bottom surface 11 of the tube, and are suitably sealed into the glass envelope at 17, 18 and 19. External connections may be made to the outer ends 20, 21 and 22 of the electrodes by suitable flexible leads (not shown). Lying within

the envelope 10 is a globule of mercury 23 adapted to make contact with the various electrodes.

The operation of this device is illustrated in Figures 1 through 4. In Figure 1, the envelope 10 is shown tipped so that the end in which the sealing-off tip 12 is located is the lower, and therefore the mercury 23 has run to this end of the tube. Electrode 14 is located immediately above the sealing-off tip 12 while electrode 15 is so formed that one end of it also extends to this end of the tube. The globule of mercury 23 is large enough so that in this position of the tube it will bridge electrodes 14 and 15, completing an external circuit associated with these two electrodes.

15 As the envelope is tipped clockwise from the position shown in Figure 1 to a position slightly past horizontal, the mercury 23 will assume the position shown in Figure 2 in which the mercury bridges all three electrodes 14, 15 and 16. The 20 mercury in this position of the tube is somewhat longer longitudinally of the tube than it would be if part of it were not lodged in depression 13 formed by the sealing-off tip 12. The mercury which lies within depression 13 adheres thereto and although the envelope is so tipped that there is a slight gradient along its lower surface 11 away from depression 13, the surface tension of the mercury is great enough to hold the portion attempting to move away from depression 13 to 30 the part lodged therein. Thus by suitably proportioning the shape of tube 10, the position of the electrodes and the amount of mercury within the tube, all three electrodes are bridged at once.

35 Tipping the envelope 10 further in a clockwise direction will establish a gradient along the bottom 11 of the envelope and away from the depression 13 that will be great enough to overcome the surface tension of the mercury and it will separate into two parts as shown in Figure 3. 40 A small portion of the mercury 23a will remain lodged in depression 13 while the greater part of the mercury 23b will flow to the other end of the tube away from depression 13 maintaining a circuit between electrodes 15 and 16 and opening 45 the circuit between electrodes 14 and 15.

As the envelope 10 is rotated counter-clockwise from the position shown in Figure 3 and when the lower internal surface 11 of the envelope becomes horizontal the mercury will assume the 50 position shown in Figure 4. The mercury 23b has left electrode 16 but has not yet reached electrode 14 and the portion of mercury 23a lying within the depression 13. Due to the fact that there is now no tension on mercury 23b, it 55

will be considerably shorter than it was in the position of the tube shown in Figure 2 and short enough so that it bridges no electrodes. Further tipping in a counter-clockwise direction will bring the various parts back into the position shown in Figure 1.

A second embodiment of the invention is shown in Figures 5 through 8. This embodiment accomplishes the same result as the previously described embodiment but in a somewhat different manner. Reference characters employed in Figure 5 apply to Figures 6, 7 and 8.

An envelope of glass or other insulating material is illustrated generally at 30. This envelope is tubular in form and includes a substantially straight lower internal surface or floor 31 and a conventional sealing-off tip 32 at one end of the envelope. The envelope surface is indented as at 33 forming a raised portion or obstacle 34 in the lower internal surface 31. Electrode 35 is positioned between one end of the envelope and the raised portion 34. Electrode 36 extends substantially parallel to the bottom 31 of envelope 30 from a point close to the raised portion 34 to a point fairly close to the other end of the tube. Electrode 37 extends within the tube to a point close to the bottom 31 of the envelope 30 and in the end thereof opposite the raised portion 34. Electrodes 35, 36 and 37 are suitably sealed in the envelope 30 as at 38, 39 and 40. Flexible lead wires, not shown, associated with external circuits may be connected to the outer ends 41, 42 and 43 of the electrodes 35, 36 and 37. A globe of mercury 44 lies within the tube 30.

In Figure 5 the end of the tube containing the raised portion 34 is shown as somewhat lower than the other end. The mercury 44 here surrounds the lower end of the electrode 35, extends over the raised portion 34 and touches one end of electrode 36. As the envelope is tipped in a clockwise direction from the position shown in Figure 5 until the bottom surface 31 of the envelope is substantially horizontal, the mercury 44 will assume the position shown in Figure 6 in which it bridges electrodes 35, 36 and 37. The raised portion 34 is so proportioned to the shape of the envelope, the amount of mercury and position of the electrodes that while there is a tendency to sheer the mercury into two parts at 34, the surface tension of the mercury is sufficient to maintain contact between all the electrodes. Further clockwise tipping of the envelope will bring it to the position shown in Figure 7, in which contact is broken between electrodes 35 and 36, the mercury all having run to the other end of the envelope making contact only between electrodes 36 and 37. Tipping the envelope counter-clockwise from the position shown in Figure 7 until the lower internal surface 31 of the envelope is just past horizontal, the mercury will have left electrode 37 and no circuits are completed. The raised portion 34 prevents the mercury 44 from flowing immediately to the other end of the tube and causes the mercury 44 to assume a length somewhat shorter longitudinally of the tube than it did in Figure 6. Further counter-clockwise tipping of the tube will cause the mercury 44 to flow over raised portion 34 and again complete the circuit between electrodes 35 and 36.

It will be seen that in both illustrated embodiments of the invention that by causing the mercury to be shorter when flowing in one direction than in the other, a single-pole double-throw switch has been provided in which the two cir-

cuits overlap in one switching operation but not in the reverse switching operation.

Various other materials and arrangements of the parts could easily be employed, and it is desired that the scope of the invention be determined only by the appended claims and prior art.

I claim as my invention:

1. In an electrical switching mechanism, in combination, an elongated container having first and second ends tiltable to a first position in which the first end is lower and to a second position in which the second end is lower, electrodes in the first end of the container for controlling a first circuit, electrodes in the second end of the container for controlling a second circuit, a body of mercury in the container for bridging the electrodes in the first end of the container when the container is in the first position and for bridging the electrodes in the second end of the container when the container is in the second position, said container having a floor provided with an irregularity near one end the remainder of the floor being so formed as to permit the flow of mercury with equal facility as the tube is tilted in either direction, the mercury being of sufficient volume to bridge the electrodes in the second end of the container before unbridging the electrodes in the first end of the container as the container is tilted from the first to the second position and for causing the mercury to unbridge the electrodes in the second end of the container before bridging the electrodes in the first end of the container as the container is tilted from the second to the first position.

2. In an electrical switching mechanism, in combination, an elongated container having first and second ends tiltable to a first position in which the first end is lower and to a second position in which the second end is lower, electrodes in the first end of the container for controlling a first circuit, electrodes in the second end of the container for controlling a second circuit, a body of mercury in the container for bridging the electrodes in the first end of the container when the container is in the first position and for bridging the electrodes in the second end of the container when the container is in the second position, the bottom of said container being straight except for an irregularity, said irregularity in the bottom of said container affecting the normal length of the mercury as the container is tilted in one direction, said irregularity having substantially no effect on the normal length of said body of mercury as said container is tilted in the opposite direction, said irregularity, in conjunction with the relative size of the container and volume of mercury, operating to cause said circuits to be overlappingly controlled as the container is tilted in a first direction and non-overlappingly controlled as said container is tilted in a second direction.

3. In an electrical switching mechanism, in combination, an elongated container having first and second ends tiltable to a first position in which the first end is lower and to a second position in which the second end is lower, electrodes in the first end for controlling a first circuit, electrodes in the second end for controlling a second circuit, the bottom of said container being straight except for an irregularity near one end thereof, a body of mercury in the container comprising a first portion which is continuously retained by said irregularity in contact with one of the electrodes in the first end of the container and a second portion movable between the first

and second ends of the container for bridging the electrodes in the first end of the container when the container is in the first position and for bridging the electrodes in the second end of the container when the container is in the second position, the volume of said second portion being such that normally when the container is horizontal the second portion will be of insufficient length to bridge all the electrodes, but when the second portion is united with the first portion and the container is tilted so that there is a slight gradient toward the second end of the container the mercury will be of a length sufficient to bridge all the electrodes.

4. In an electrical switching mechanism, in combination, a cylindrical container having first and second ends tiltable to a first position in which the first end is lower and to a second position in which the second end is lower the bottom of said container being straight except for an obstruction in the first end thereof, electrodes in the first end of the container for controlling a first circuit, electrodes in the second end of the container for controlling a second circuit, a body of mercury in the container for bridging the electrodes in the first end of the container when the container is in the first position and for bridging the electrodes in the second end of the container when the container is in the second position and being of a volume sufficient to bridge the electrodes in the second end of the container before unbridging the electrodes in the first end of the container as the container is tilted from the first position to the second position, said ob-

struction in the first end of the container having a height sufficient to restrain the movement of the mercury toward the first end of the container when the container is tilted from the second toward the first position until the mercury unbridges the electrodes in the second end of the container.

5. In an electrical switching mechanism, in combination, a cylindrical container having first and second ends tiltable to a first position in which the first end is lower and to a second position in which the second end is lower, a well in the first end of the container formed by the sealing-off tip of the container, electrodes in the first end for controlling a first circuit, electrodes in the second end for controlling a second circuit, a body of mercury in the container comprising a first portion which is continuously retained by the well and a second portion movable between the first and second ends of the container for bridging the electrodes in the first end of the container when the container is in the first position and for bridging the electrodes in the second end of the container when the container is in the second position, the volume of said second portion of mercury being such that when the container is horizontal and is being tilted from the second to the first position said second portion will assume a length less than sufficient to bridge all the electrodes, but when united with the first portion and the container is tilted from the first position to the second position will assume a length sufficient to bridge all the electrodes.

ROBERT S. CRAIG.
